(57) **CLAIM**

The ornamental design for a bucket clamp, as shown and described.

DESCRIPTION

FIG. 1 is a front, top and right side perspective view of the bucket clamp showing our new design;

FIG. 2 is a right side elevational view thereof; the left side elevational view being a mirror image thereof;

FIG. 3 is a top plan view thereof;

FIG. 4 is a front elevational view thereof;

FIG. 5 is a rear elevational thereof; and,

FIG. 6 is a bottom plan view thereof.

The broken lines in FIGS. 1-6 are for illustrative purposes only and form no part of the claimed design.
